US00D950295S

(12) **United States Design Patent** (10) Patent No.: **US D950,295 S**
(45) Date of Patent: **** May 3, 2022**

(54) **FOOD PROCESSOR**

(71) Applicant: **BABYLISS FACO SRL**, Wandre (BE)

(72) Inventor: **Aubry Ernote**, Theux (BE)

(73) Assignee: **BABYLISS FACO SRL**, Wandre (BE)

(**) Term: **15 Years**

(21) Appl. No.: **35/510,848**

(22) Filed: **Nov. 18, 2020**

(80) **Hague Agreement Data**

Int. Filing Date: **Nov. 18, 2020**

Int. Reg. No.: **DM/211346**

Int. Reg. Date: **Nov. 18, 2020**

Int. Reg. Pub. Date: **Dec. 4, 2020**

(30) **Foreign Application Priority Data**

May 22, 2020 (EM) 007960984-0001

Primary Examiner — Karen S Acker

(57) **CLAIM**

The ornamental design for a food processor, as shown and described.

DESCRIPTION

The patent or application file contains at least one drawing executed in color. Copies of this patent or patent application publication with color drawing(s) will be provided by the Office upon request and payment of the necessary fee.

1. Food processor

1.1: front and left perspective

1.2: front

1.3: rear

1.4: right

1.5: left

1.6: top

1.7: bottom

1.8: rear and right perspective

**1 Claim, 8 Drawing Sheets
(8 of 8 Drawing Sheet(s) Filed in Color)**
